UNITED STATES PATENT OFFICE.

OSBORNE H. SHEPPARD, OF CHICAGO, ILLINOIS, ASSIGNOR TO W. N. SHARP, OF CHICAGO, ILLINOIS.

EAR-TRUMPET.

1,079,670.

Specification of Letters Patent.

Patented Nov. 25, 1913.

Application filed June 14, 1913. Serial No. 773,749.

To all whom it may concern:

Be it known that I, OSBORNE H. SHEPPARD, a citizen of the United States, residing at Chicago, in the county of Cook and 5 State of Illinois, have invented a new and useful Improvement in Ear-Trumpets, of which the following is a specification.

My invention relates to an improvement in ear-trumpets, which I have devised, more 10 immediately, for use in the kind of such devices known in the trade as "conversational tubes," in which a flexible tube has connected with one end a flaring or bell-shaped mouth-piece, and with its opposite end a rigid 15 curved tube-section to be inserted into the ear of the user, while the voice of the person talking is directed into the mouth-piece. In an ear-trumpet of this conversational-tube variety, particularly, the voice, in carrying 20 through it, produces a roaring sound, which is not only disagreeable to the listener, but muffles, more or less, the sound of the voice, thus impairing its desirable distinctness; and the object of my invention is 25 to correct this defect.

In the accompanying drawing, Figure 1 is a view in elevation of an ear-trumpet provided with my improvement; Fig. 2 is an enlarged plan view of the same, looking 30 into the mouth-piece, and Fig. 3 is a section on line 3, Fig. 2.

The mouth-piece 4, of general funnel-shape, has its shouldered stem connected with one end of a flexible tube 5, into the 35 opposite end of which is inserted a stiff tube 6, curved for convenience in inserting it into the ear; all as is common in devices of the present kind.

My invention consists in an outwardly-bulging button-like plate 7, of the preferred 40 concavo-convex disk shape illustrated, interposed in the mouth-piece and rigidly fastened to diametrically-opposite points therein, at ears 8 projecting from the plate, by 45 soldering, if the parts be formed of metal, as are those in the sample illustrated in the drawing. The edge of the plate 7 between the opposite ears is thus spaced from the

inner wall surface of the mouth-piece; and in talking into the latter the sound of the voice, directed against the convex surface of the plate, is diffused over the plate through the space and transmitted through the flexible tube to the listener's ear. The effects of the interposed plate 7 are, though 50 I am unable to state the reason therefor, to entirely prevent roaring sound in the use of the device, and to enhance the clearness, at the receiving end, of the sound transmitted at the mouth-piece. It will be observed 55 however that by reason of the rounded or convex surface of the plate 7 and the inclined inner wall of the mouth-piece 4, the sound waves entering the trumpet are caused to travel over the inclined surfaces 60 in a substantially straight path, thus avoiding all sharp edges or corners calculated to break up such sound waves, and thereby diminish the efficiency of a device of this character.

What I claim as new and desire to secure by Letters Patent is,—

In an ear-trumpet, the combination with a flexible tube provided at one of its ends with an inflexible tubular section adapted 75 for insertion in the ear, and at its opposite end with a mouth-piece having a reduced tubular inner end adapted to be inserted in said flexible tube and an outer end outwardly flaring therefrom, of a concavo-convex disk located entirely within said flaring mouth-piece approximately centrally thereof and spaced about its edge from the flared wall surface of such mouth-piece, the said disk being located sufficiently far from 80 the mouth of the mouth-piece so that all the sound waves that strike said disk will be deflected against the inner wall of the mouthpiece and diffused over rounded surfaces into the flexible tube, for the purpose 85 set forth.

OSBORNE H. SHEPPARD.
